JAMES HUTCHISON, OF NEWARK, NEW JERSEY, ASSIGNOR TO THOMAS POTTER, SON & CO., OF PHILADELPHIA, PENNSYLVANIA.

Design No. 4,403, dated October 11, 1870.

DESIGN FOR AN OIL-CLOTH PATTERN.

The Schedule referred to in these Letters Patent and making part of the same.

I, JAMES HUTCHISON, of Newark, county of Essex, state of New Jersey, have invented or produced a design for an Oil-Cloth Pattern, of which the following is a specification.

The figure in the accompanying drawing represents, partly in outline and partly filled in with ornaments, a design for an oil-cloth pattern, the main characteristics of which consists of tablets A A, formed and arranged in respect to each other and to figures B, the manner clearly shown in outline.

Each tablet is ornamented by a design, one-fourth of which is illustrated at a, sufficient of the design of ornaments B being shown to define their character.

Each oblong space D, between the tablets, has an ornament, e, too clearly shown in the drawing to need explanation.

I. claim—

1. Irrespective of the ornamentation of the tablet A, an oil-cloth pattern, composed of a series of the said tablets A, formed and arranged in respect to each other and the figures B, as set forth.
2. Tablets A, ornamented as shown.
3. The design composed of the ornaments e, ornamented tablets A, and figures B.

In testimony whereof, I have signed my name to this specification in the presence of two subscribing witnesses.

JAMES HUTCHISON.
